UNITED STATES PATENT OFFICE.

FRANK PARIZEK, OF CHICAGO, ILLINOIS.

WHISTLE.

Application filed November 1, 1924. Serial No. 747,236.

To all whom it may concern:

Be it known that I, FRANK PARIZEK, a citizen of the United States, residing at Chicago, in the county of Cook and State 5 of Illinois, have invented a certain new and useful Improvement in Whistles, of which the following is a full, clear, concise, and exact description, reference being had to the accompanying drawings, forming a part of 10 this specification.

My invention relates to whistles, and more particularly to exhaust whistles.

The purpose of my invention is to provide a whistle of the above mentioned character 15 that comprises a one piece body portion and an outer shell mounted thereon, said outer shell being preferably shrunk on the body portion.

It is a further purpose of the invention, 20 to provide a whistle of the above mentioned character in which the body portion is made in one piece and preferably of a metal that expands more rapidly than the metal of the outer shell so that upon heating of the 25 whistle due to the exhaust gases passing through the same, the outer shell will be held more firmly in position the hotter the parts of the whistle get. The whistle is preferably made of an aluminum casting comprising 30 longitudinally extending wall portions, transverse partitions and end wall portions, the body portion having a chamber at one end thereof into which a connection from the exhaust pipe enters, and an outer shell 35 of brass, the brass having a lower coefficient of expansion than the aluminum, thus providing for a tight joint between the shell and the body portion as referred to above.

It is another purpose of the invention to 40 provide orifices leading from the chamber in one end of the casing to the passages defined by the longitudinally extending walls of the body portion, said orifices being formed by means of elongated recesses in the end wall 45 at one end of the chamber and slots in the side wall portion of the chamber, said slots being relatively wide to prevent clogging thereof.

Other objects and advantages of the invention will appear as the description of the 50 accompanying drawings proceeds. However, I desire to have it distinctly understood that I do not intend to limit myself to the exact details shown or described, but 55 that I intend to include as part of my invention all such obvious changes and modi-

fications of parts as would occur to a person skilled in this art and as would fall within the scope of the claims.

In the drawings:

Fig. 1 is a side elevation of my improved whistle;

Fig. 2 is a similar view partly broken away of the body portion thereof;

Fig. 3 is a section taken on the line 3—3 65 of Fig. 1; and

Fig. 4 is a section taken on the line 4—4 of Fig. 1.

Referring in detail to the drawings, the whistle comprises a body portion 10 having 70 a plurality of longitudinally extending walls 11, 12, 13, and 14, said walls preferably extending radially from the central portion 15 of the body portion 10. The walls 11, 12, 13, and 14 define longitudinally extending 75 passages 16, 17, 18, and 19.

One end of the body portion is provided 80 with an internally screw threaded projection 20 that is preferably made with flat faces so as to provide means for turning the 85 whistle on to the screw threaded end of the pipe by a wrench or similar tool. The end of the body portion having the screw threaded member 20 thereon has a side wall portion 21 and an end wall portion 22 defining a chamber 23. The side wall 21 is provided with a plurality of elongated wide slots 24 and the end wall portion 22 has a corresponding groove or recess 25 therein, thus providing elongated angular passages 90 between the outer shell 26 and the body portion 10 leading from the chamber 23 outwardly through the arcuate spaces provided 95 between the thin portions 27 of the side wall 21 and the grooves 25 in the end wall 22. 100

The shell 26 is in the form of a circular band which is a short section of a tube and which fits snugly on the curved wall portion 28 of the member 10 at one end thereof as is clearly shown in Fig. 1.

The body portion is further provided with 105 an end wall portion 29 at the opposite end thereof which has a curved edge portion which is of substantially the same diameter as the curved wall portion 28. Certain of said longitudinally extending walls are provided with cut away portions 30 to provide wall portions of reduced height 31 and transverse partitions such as 32 and 33 are provided to provide various lengths of columns 110 of air in the passages defined between the longitudinally extending walls. An outer tu-

bular casing on shell 34 is provided on the body portion 10 and fits snugly on the edges of the longitudinally extending members 11, 12, 13, and 14 and the end portion 29. It will be seen that due to the provision of the openings 30, certain of the longitudinally extending passages are increased in their effective length due to the addition of the portion of the adjoining longitudinal passage way between the partition and the end wall thereto. As for example, in Fig. 2, the portion 35 between the end wall 29 and the partition 32 is added to the length of the passage 19 provided between the walls 11 and 14 and in a similar manner the portion 36 between the partition 33 and the end wall 29 is added to the length of the passage 17. Thus, the passage 16 is the shortest, the passage 18 is next in length, the passage 17 is still longer and the passage 19 is the longest.

The tubular member 34 is spaced from the tubular member 26 to provide an opening 37 therebetween, thereby providing an opening in the bottom of each column of air or pipe 25 in the whistle. The member 10 comprising the longitudinal walls 11, 12, 13 and 14, the end portion forming the chamber 23 and the end wall 29 as well as the partitions 32 and 33 is cast in one piece preferably of aluminum. The tubular members 26 and 34 forming the shell are preferably made of brass tubing. The members 26 and 34 are preferably shrunk on the member 10 and due to the fact that the material of the member 10 has a higher coefficient of expansion than the shell made up of the members 26 and 34, the heating up of the whistle in use due to the passage of the exhaust gases therethrough will cause a more rapid expansion of the aluminum body portion than the brass tubing and as a result will hold the parts in position with an increasing pressure as the device heats up.

Having thus described my invention, what I desire to claim and secure by United States Letters Patent is:

1. A whistle of the character described comprising a body portion having a plurality of substantially radially extending walls, end walls integral therewith, a plurality of transverse partitions and a tubular shell shrunk on said body portion to provide a plurality of longitudinally extending chambers therein, certain of said radial walls being interrupted on one side of said partitions, whereby certain of said chambers have portions lying endwise beyond an adjoining chamber.

2. A whistle of the character described comprising a body portion having a plurality of longitudinally extending walls, end walls, transversely extending partitions on said body portion and a casing surrounding

said body portion to provide a plurality of longitudinally extending chambers therein, certain of said longitudinally extending walls being interrupted on one side of said partition, whereby certain of said chambers have portions lying endwise beyond an adjoining chamber.

3. A whistle of the character described comprising a body portion having a plurality of substantially radially extending walls, end walls integral therewith, a tubular shell surrounding said body portion to provide a plurality of longitudinally extending chambers therein, a chamber in one end of said body portion and orifices leading into said longitudinally extending chambers from said end chamber certain of said radial walls being interrupted, whereby the portion of said longitudinal chamber on one side of the partitions adjacent thereto serves as an extension of the adjoining longitudinal chamber.

4. A whistle of the character described comprising an outer shell and an inner body portion closely engaging said shell, said body portion being of material having a greater co-efficient of expansion than said shell whereby heating of said whistle tightens said shell on said body portion.

5. A whistle of the character described comprising an outer shell and an inner body portion shrunk on said shell, said body portion being of material having a greater co-efficient of expansion than said shell whereby heating of said whistle tightens said shell on said body portion.

6. A whistle of the character described comprising an outer shell and an inner body portion having longitudinal walls, end walls and transverse partitions integral therewith closely engaging said shell, said body portion being of material having a greater co-efficient of expansion than said shell whereby heating of said whistle tightens said shell on said body portion.

7. A whistle of the character described comprising an inner aluminum body portion and outer brass shell shrunk thereon.

8. A whistle of the character described comprising a body portion having a chamber in one end thereof, a plurality of longitudinally extending walls defining passages therebetween extending from one end wall of said chamber, said end wall having recesses therein and the side wall portion of said chamber having wide slots therein leading to said recesses, and an outer shell surrounding said body portion.

In witness whereof, I hereunto subscribe my name this 23rd day of October, A. D. 1924.

FRANK PARIZEK.
